TAG PATCHING MACHINE

Filed Oct. 29, 1930

UNITED STATES PATENT OFFICE

CLARENCE A. FARRAR, OF WHITMAN, MASSACHUSETTS, ASSIGNOR TO ANDREW J. FISH,
OF BROCKTON, MASSACHUSETTS

TAG PATCHING MACHINE

Application filed October 29, 1930. Serial No. 491,999.

This invention relates to a machine organized to cut reinforcing patches from a gummed patch strip, and press the patches against tags.

5 The patches are cut by male and female dies acting within a fixed guide having a slot through which the gummed strip passes in the path of the male die.

10 The gum on the patch strip is necessarily in a soft and tacky condition during the operation of the machine.

15 Heretofore in a machine of the character stated the tacky gum through which the male die passes has been allowed to accumulate on the male die and harden thereon to such an extent that it has been necessary to frequently remove the guides and dies from the machine for the purpose of cleaning the dies, much time being thus lost. Moreover, accumulations of hardened gum increases the wear of the dies and reduces the term of their operativeness.

20 The object of my invention is to prevent the accumulation of gum on the dies, the necessity of stopping the machine for the purpose above stated, and the increased wear of the dies caused by the accumulation of hardened gum thereon.

25 Of the accompanying drawings forming a part of this specification,—

Figures 1 and 2 are side views of a portion of a tag patching machine in which my invention may be embodied.

30 Figure 3 is a section on line 3—3 of Figure 1.

Figure 4 is a section on line 4—4 of Figure 1.

35 Figure 5 shows in perspective the elements of the die lubricator hereinafter described.

40 Figure 6 is an enlargement of a portion of Figure 3 showing portions of two guides, portions of two pairs of dies, and two lubricators.

45 The same reference characters indicate the same parts in all of the figures.

A tag patching machine to which my invention relates includes a supporting frame 12, tubular guides 13 fixed to the frame with their bores in alignment with each other, the adjacent ends of the guides being spaced

apart and a fixed table 14 projecting between the adjacent ends of the guides on which a tag 15 is placed to receive the patches.

The guides 13 are provided with slots 16 arranged to guide gummed strips 17 across the bores of the guides. Each guide 13 is provided with a fixed female cutting die 18 adapted to cooperate with a movable male cutting die 19 which is reciprocated in the bore of the guide by any suitable mechanism 22 adapted to alternately project and retract the male die. When the die is retracted a portion of the bore of each guide forms a space 20 beyond the cutting end of the retracted die, said space being below the cutting end of the upper die as shown by Figure 3. Said dies have circular cutting edges, the cutting edge of the male die being formed by the intersection of the circular periphery of the die and a pressing end face at the forward end 70 of the die, said face being adapted to press a detached patch against a tag 15.

A machine organized as above briefly described is well known, and its general organization is not claimed by me, the novel 75 feature of my invention consisting in oil applying means located in the space 20 and adapted to apply a film of oil to the male die when it is being projected and retracted, and thereby prevent an accumulation of gum 80 on said die.

A sufficient understanding of the invention is afforded by the following description of the oil applying means associated with the upper guide, said means being identical 85 in the two guides.

I embody said oil applying means in a lubricator located in the space 20, and comprising an oil conducting applicator 21 conformable to the periphery of the male die, 90 and means for securing said applicator in the bore of the guide in position to apply a film of oil to the male die when it is being projected and retracted.

The applicator 21 is an annulus preferably 95 of felt or other suitable compressible absorbent material the internal diameter of the annular applicator being less than the diameter of the male die 19, so that the applicator has wiping contact with a considerable por- 100

tion of the die when the latter is moved in the applicator.

The means for securing the applicator in its operative position is embodied in rigid 5 clamping rings 22 and 23 engaged with the bore of the guide and bearing on opposite sides of the applicator, the internal diameter of said rings being larger than that of the cutting end of the male die so that the die 10 cannot contact with the rings. The upper ring 22 is formed to permit oil to flow through it to the applicator, and for this purpose is preferably provided with oil passages 24. When the lubricator is associated with the 15 upper guide 13 oil may be conducted to the lubricator through a longitudinal groove 25 (Figures 3 and 4) in a carrier 26 to which the upper die is fixed.

When the male die is projected and enters 20 the female die 18 some of the oil applied to the male die contacts with the female die and prevents an accumulation of gum thereon.

The inner edge of the applicator projects 25 inwardly from the inner margins of the rings 22 and 23, as best shown by Figure 6, to a sufficient extent to be compressed by the periphery of the male die when the latter is rising through the applicator, so that a film of oil is applied to a portion of said periphery. When the cutting edge of the male die 30 rises above the applicator, the inner edge of the latter springs inwardly and applies a film of oil to the marginal portion of the end face of the male die. When the male die descends its cutting edge again compresses the 35 inner edge of the applicator which first wipes oil upon the marginal portion of the end face, and then upon a portion of the periphery of the male die.

40 The clamping rings 22 and 23 preferably have a tight friction fit in an enlargement of the bore of the guide 13, one end of said enlargement forming a shoulder 28 on which the ring 22 abuts.

45 The ring 23 is preferably provided with narrow gripping edges 27 (Figure 5) which indent the applicator and prevent edgewise displacement of the clamped portion thereof.

50 I have found by practical tests that the cutting dies of a machine which includes oil applying means embodying the invention, do not acquire accumulations of hardened gum and therefore do not require cleaning.

55 It will be understood that my invention is not concerned with details of mechanism shown by the drawings and not hereinbefore described and hereinafter claimed.

I claim:

60 A tag-patching machine which includes a fixed tubular guide having means for guiding a gummed patch strip, and male and female cutting dies adapted to cut patches from said strip, the cutting edge of the male die being formed by the intersection of the periphery 65 and a pressing end face of the die, the fe-

male die being fixed in the guide, and the male die movable and reciprocated therein, the cutting edge of the male die being within the core of the tubular guide when the die is retracted, so that a portion of the die 70 forms a space extending beyond the cutting edge of the retracted die, the machine being characterized by a lubricator located in said space, adapted to apply oil to portions of the periphery and end face of the male die and prevent the accumulation of patch strip gum 75 thereon, said lubricator comprising an annular applicator of compressible absorbent material, and rigid clamping rings fixed in the bore of the guide and bearing on opposite 80 sides of the major portion of the applicator, the internal diameter of said rings being greater than that of the cutting edge of the male die, so that said edge is adapted to pass through said rings without contact therewith, the internal diameter of the applicator being less than that of said cutting edge, so that the inner edge of the applicator projects inwardly from the inner margins of said rings and has a yielding wiping contact with portions of the periphery and end face of the male die when the latter is reciprocated, whereby a film of oil is deposited on each of said portions.

In testimony whereof I have affixed my signature.

CLARENCE A. FARRAR.
